UNITED STATES PATENT OFFICE.

PETER N. LANDINE, OF MILFORD, CONNECTICUT, ASSIGNOR OF ONE-HALF TO WILLIAM B. McCARTHY, OF MILFORD, CONNECTICUT.

FENDER FOR STREET-RAILWAY CARS.

984,277.

Specification of Letters Patent.

Patented Feb. 14, 1911.

Application filed April 13, 1910. Serial No. 555,209.

To all whom it may concern:

Be it known that I, PETER N. LANDINE, a citizen of the United States, residing at Milford, in the county of New Haven and State of Connecticut, have invented a new and useful Improvement in Fenders for Street-Railway Cars; and I do hereby declare the following, when taken in connection with the accompanying drawings and the letters of reference marked thereon, to be a full, clear, and exact description of the same, and which said drawings constitute part of this specification, and represent, in—

Figure 1 a side view of a fender for street railway cars constructed in accordance with my invention. Fig. 2 a top or plan view of one side of the same, with the tripping rod omitted. Fig. 3 a broken sectional view on the line *a—b* of Fig. 2 looking outward and on an enlarged scale. Fig. 4 a broken sectional view illustrating the connection of the tripping bar with the rock shaft. Fig. 5 a view in rear elevation of one of the yokes and parts connected therewith.

This invention relates to an improvement in fenders for street railway cars, particularly of that class which is adapted to be folded up against the dash board and dropped down either by means operated from the platform, or when it strikes an obstruction, the object being an effective construction with comparatively few parts; and the invention consists in the construction hereinafter described and particularly recited in the claims.

The basket or catcher is a rectangular frame having an upper bar 2, lower bar 3 and side bars 4. As both sides of the device are the same, but one side is illustrated. These bars support straps 5, or if preferred, a net. The upper bar is pivotally mounted in arms 6 which project rearwardly through brackets 7 attached to the underside of a platform 8, the bracket 7 having a downwardly projecting cam-arm 9 for a purpose as will hereinafter appear.

Pivottally mounted at the outer ends of the top bar 2 are yokes 10 which extend downward and carry locking-pins 11 adapted to engage with the ends of braces 12 secured to the rear ends of the arms 6. The attachment of the yokes with the braces 12 is such as to permit convenient disengagement, and to this end the upper edge of the forwardly extending portion of each brace

12 is formed with a notch 13, and the pins 11 are each formed with a notch 14 and so that when the pins are turned with the notches downward the ends of the braces may enter the yokes and then if the pins are given a half turn, they will extend into the notches and thus lock the yokes with the braces. The yokes 10 are connected together by a transverse rock shaft 19. This is preferably square throughout its main portion 60 with rounded ends which project through the yoke, and on the ends of this shaft within the yokes are mounted links 15 connected by a pivot 16 with links 17 which links 17 are connected at their outer ends with arms 70 18 rigidly secured to the side bars 4. When these links are in line the outer end of the frame will be held somewhat above the roadway and the extent of elevation of the outer end may be changed by changing the point 75 of attachment of the links 17 with the arms 18. Thus when the links 17 are coupled with the arms 18 as shown in Fig. 2 of the drawings, the outer end of the frame will be slightly elevated, but if the links 17 are 80 connected with the arms 18 at the ends of the arms and through the holes 30, the outer end of the frame will be raised to a greater extent.

Secured to a square portion of the rock 85 shaft 19 near the yokes 10 are S-shaped or cam levers 20 the forward ends of which are connected with a pivot 16 and the rear ends of which extend rearwardly into the path of the cam-arm 9 and so that rearward movement of the basket will move the yoke rearward, the rearward movement of the yoke forcing the arms 6 and the braces 12 rearward against the action of the springs 24. The rearward movement of the yoke will 95 carry the cam-lever 20 against the cam arm and trip the lever so as to turn the links 15 and 17 out of line with each other so as to allow the outer end of the fender frame to drop. Beyond the lower bar 3 of the basket 100 is a transverse tripping rod 21 which is connected by long rods 22 with arms 23 secured to the rock shaft 19 and so that if the tripping arm 21 is forced rearward it will turn the rock-shaft and draw the links 15 and 105 17 out of alinement so as to cause the outer end of the basket to drop. As before stated, the arms 6 are adapted to move rearwardly in the brackets 7, and to hold them normally in their outer position a heavy spiral spring 110

- 24 is arranged on the arms 6, the spring bearing at one end against the bracket and at the opposite end against a washer 25 rigidly secured to the arm 6.
- 5 To drop the fender from the platform the rock shaft 19 is further provided with a downwardly projecting arm 26 which is connected by a link 27 with a bell-crank lever 28 adapted to be turned by a foot lever 29 from any convenient point on the platform. In meeting an obstruction, if the tripping rod 21 strikes it, the arms 22 will be forced rearward so as to turn the rock-shaft 19 and throw the links 15 and 17 out of line so that the outer end of the basket may drop, or in case the tripping rod is not employed, the outer or lower bar 3 of the frame, if forced rearward, will cause the cam-lever 20 to engage with the lower end 10 of the cam-arm 9 and be turned thereby so as to throw the links 15 and 17 out of alignment and cause the outer end of the basket to drop, and the basket may also be dropped from the platform by depressing 15 the lever 29.
- When it is desired to turn the basket up against the front of the car, the pins 11 are turned to disengage the lower ends of the yokes from the outer ends of the braces so 20 that the basket may be turned upward as shown in broken lines in Fig. 1.
- I claim:—
1. A fender for street railway cars comprising a basket having its upper bar pivotally connected with rearwardly projecting arms which are longitudinally movable in brackets secured to the underside of the car platform, yokes depending from said upper bar, braces connected with said arms 25 and with the lower ends of said yokes, a pair 30 of links connected with said yokes and with said frame, a rock shaft parallel with said upper bar, a cam-lever connected with said rock shaft and with said links, and means 35 for turning said shaft whereby said links are thrown out of alignment.
2. A fender for street railway cars comprising a basket having its upper bar pivotally connected with rearwardly projecting arms which are longitudinally movable in brackets secured to the underside of the car platform, yokes depending from said upper bar, braces connected with said arms 40 and with the lower ends of said yokes, a pair of links connected with said yokes and with said frame, a rock shaft parallel with said upper bar, a cam-lever connected with said rock shaft and with said links, and means 45 for turning said shaft whereby said links are thrown out of alignment.
3. A fender for street railway cars comprising a basket having its upper bar pivotally connected with rearwardly projecting arms which are longitudinally movable in brackets secured to the underside of the car platform, yokes depending from said upper bar, braces connected with said arms 50 and with the lower ends of said yokes, a pair of links connected with said yokes and with said frame, a rock shaft parallel with said upper bar, a cam-lever connected with said rock shaft and with said links, and means for turning said shaft whereby said links are thrown out of alignment.
4. A fender for street railway cars comprising a basket having its upper bar pivotally connected with rearwardly projecting arms which are longitudinally movable in brackets secured to the underside of the car platform, yokes depending from said upper bar, braces connected with said arms 55 and with the lower ends of said yokes, a pair of links connected with said yokes and with said frame, a rock shaft parallel with said upper bar, a cam-lever connected with said rock shaft and with said links, and means for turning said shaft whereby said links are thrown out of alignment.
5. A fender for street railway cars comprising a basket having its upper bar pivotally connected with rearwardly projecting arms which are longitudinally movable in brackets secured to the underside of the car platform, yokes depending from said upper bar, braces connected with said arms 60 and with the lower ends of said yokes, a pair of links connected with said yokes and with said frame, a rock shaft parallel with said upper bar, a cam-lever connected with said rock shaft and with said links, and means for turning said shaft whereby said links are thrown out of alignment.
6. A fender for street railway cars comprising a basket having its upper bar pivotally connected with rearwardly projecting arms which are longitudinally movable in brackets secured to the underside of the car platform, yokes depending from said upper bar, braces connected with said arms 65 and with the lower ends of said yokes, a pair of links connected with said yokes and with said frame, a rock shaft parallel with said upper bar, a cam-lever connected with said rock shaft and with said links, and means for turning said shaft whereby said links are thrown out of alignment.
7. A fender for street railway cars comprising a basket having its upper bar pivotally connected with rearwardly projecting arms which are longitudinally movable in brackets secured to the underside of the car platform, yokes depending from said upper bar, braces connected with said arms 70 and with the lower ends of said yokes, a pair of links connected with said yokes and with said frame, a rock shaft parallel with said upper bar, a cam-lever connected with said rock shaft and with said links, and means for turning said shaft whereby said links are thrown out of alignment.
8. A fender for street railway cars comprising a basket having its upper bar pivotally connected with rearwardly projecting arms which are longitudinally movable in brackets secured to the underside of the car platform, yokes depending from said upper bar, braces connected with said arms 75 and with the lower ends of said yokes, a pair of links connected with said yokes and with said frame, a rock shaft parallel with said upper bar, a cam-lever connected with said rock shaft and with said links, and means for turning said shaft whereby said links are thrown out of alignment.
9. A fender for street railway cars comprising a basket having its upper bar pivotally connected with rearwardly projecting arms which are longitudinally movable in brackets secured to the underside of the car platform, yokes depending from said upper bar, braces connected with said arms 80 and with the lower ends of said yokes, a pair of links connected with said yokes and with said frame, a rock shaft parallel with said upper bar, a cam-lever connected with said rock shaft and with said links, and means for turning said shaft whereby said links are thrown out of alignment.
10. A fender for street railway cars comprising a basket having its upper bar pivotally connected with rearwardly projecting arms which are longitudinally movable in brackets secured to the underside of the car platform, yokes depending from said upper bar, braces connected with said arms 85 and with the lower ends of said yokes, a pair of links connected with said yokes and with said frame, a rock shaft parallel with said upper bar, a cam-lever connected with said rock shaft and with said links, and means for turning said shaft whereby said links are thrown out of alignment.
11. A fender for street railway cars comprising a basket having its upper bar pivotally connected with rearwardly projecting arms which are longitudinally movable in brackets secured to the underside of the car platform, yokes depending from said upper bar, braces connected with said arms 90 and with the lower ends of said yokes, a pair of links connected with said yokes and with said frame, a rock shaft parallel with said upper bar, a cam-lever connected with said rock shaft and with said links, and means for turning said shaft whereby said links are thrown out of alignment.
12. A fender for street railway cars comprising a basket having its upper bar pivotally connected with rearwardly projecting arms which are longitudinally movable in brackets secured to the underside of the car platform, yokes depending from said upper bar, braces connected with said arms 95 and with the lower ends of said yokes, a pair of links connected with said yokes and with said frame, a rock shaft parallel with said upper bar, a cam-lever connected with said rock shaft and with said links, and means for turning said shaft whereby said links are thrown out of alignment.
13. A fender for street railway cars comprising a basket having its upper bar pivotally connected with rearwardly projecting arms which are longitudinally movable in brackets secured to the underside of the car platform, yokes depending from said upper bar, braces connected with said arms 100 and with the lower ends of said yokes, a pair of links connected with said yokes and with said frame, a rock shaft parallel with said upper bar, a cam-lever connected with said rock shaft and with said links, and means for turning said shaft whereby said links are thrown out of alignment.

In testimony whereof, I have signed this specification in the presence of two subscribing witnesses.

PETER N. LANDINE.
